UNITED STATES PATENT OFFICE.

JOSEPH BEHLE, OF DALLAS, TEXAS, ASSIGNOR TO THE MURRAY COMPANY, OF DALLAS, TEXAS, A CORPORATION OF TEXAS.

COTTON-HANDLING DRUM.

Application filed November 12, 1928. Serial No. 318,976.

This invention relates to new and useful improvements in cotton handling drums.

One object of the invention is to provide a drum involving certain novel structural features making for economy in manufacture and efficiency in operation as well as stability in use.

Another object of the invention is to provide a drum wherein longitudinal radial flanges or beaters are formed by constructing the drum cylinder of segments of sheet metal, bending the longitudinal edges of the segments into flanges and bolting the flanges together.

15 A further object of the invention is to combine with the drum spiders, fan blades for drawing air into the drum as it is revolved.

Still another object of the invention is to securely mount radial metal pins in the 20 drum cylinder.

Another object of the invention is to provide each end of the drum with a screen, whereby lint, fibres and other trash is excluded and cannot be drawn in with the air. 25 By this arrangement clogging of the drum and plugging of the air emitting perforations is avoided.

A construction designed to carry out the invention will be hereinafter described, together with other features of the invention.

The invention will be more readily understood from a reading of the following specification and by reference to the accompanying drawings, in which an example of the invention is shown, and wherein:

Fig. 1 is an isometrical view of a drum constructed in accordance with the invention,

Fig. 2 is an end elevation of one end of the drum,

40 Fig. 3 is an elevation of the opposite end of the drum,

Fig. 4 is an enlarged sectional view through a portion of the drum, and

Fig. 5 is an end elevation of the drum of 45 Fig. 1 showing a screen applied thereto.

In the drawings the numeral 10 designates one of the segments of which the drum cylinder is composed. Each segment is formed of an elongated sheet of metal curved to fit on end rings 11 forming part of the end spiders.

Along the longitudinal edges of the segment the metal is bent outwardly to form flanges 12. The flanges of one segment lie against and are secured to the flanges of the next adjacent segment by transverse bolts 13. The 55 segments are secured on the rings 11 by bolts 14 (Fig. 4) and the rings are set inwardly from the ends of the drum.

The drum has spiders at each end formed by the rings 11 and fan blades 15 and 16 respectively, made integral with the rings. The blades 15 (Fig. 2) are twisted oppositely to the blades 16 (Fig. 3), so that when the drum is revolved in the direction of the arrows air will be drawn into the drum from 60 both ends. A shaft 21 may be fastened in the hubs of the spiders.

On the advance side of the beaters formed by the flanges 12, each segment has a row of perforations or orifices 17. When the drum 70 is revolved in the direction of the arrows, air drawn in by the fan spiders will be expelled through the perforations 17 by centrifugal action. The perforations being contiguous to the flanges, said flanges or beaters act to 75 deflect the air emitted from the perforations.

Where the drum is used in a cotton gin feeder or other machine requiring the material being handled to be moved by the drum, pins or studs 18 are mounted in the 80 segments between the flanges. These pins may be arranged in rows or otherwise. Each pin may be welded, screwed into or otherwise fastened to the sheet, but I prefer to provide each pin with an integral collar 85 19 resting on the outer surface of the sheet, while the shank below the collar penetrates the sheet and is headed at 20 on the under side of the sheet, whereby the pin is fastened.

It is within the scope of the invention to equip each end of the drum with a screen 21, preferably secured to the ring 11 or between the ring and the inner surfaces of the segments 10. It is desirable to place 95 the screens in rear of the fan blades 15 and 16, but the screens could be otherwise mounted in the ends of the drums.

Such screens will prevent lint, fibres and trash being drawn into the drum and clog- 100

ging the same or plugging the perforations 17. It is to be understood that the screens may be omitted, particularly where air is supplied to the ends of the drum through 5 screened openings.

Various changes in the size and shape of the different parts, as well as modifications and alterations, may be made within the scope of the appended claims.

10 What I claim, is:

1. A tubular drum comprising a plurality of segmental sheets having longitudinal flanges formed therefrom along each edge, said flanges being secured together to form 15 beaters on the outer surface of the drum, and means at the ends of the drum on which the sheets are mounted to permit passage of air through the drum.

2. A drum comprising a plurality of segmental perforated sheets having longitudinal flanges formed therefrom along each edge, said flanges being secured together to form beaters on the outer surface of the drum, spider arms at the ends of the drum on which the sheets are mounted, and pins 25 mounted on the sheets between the flanges.

3. A drum comprising a plurality of segmental sheets having longitudinal flanges formed therefrom along each edge, said flanges being secured together to form beaters on the outer surface of the drum, and spiders at the ends of the drum on which the sheets are mounted, the sheets having air emitting perforations and the ends of 35 the drum being open for admitting air.

4. A drum comprising a plurality of segmental sheets having longitudinal flanges formed therefrom along each edge, said flanges being secured together to form beaters on the outer surface of the drum, spiders at the ends of the drum on which the sheets are mounted, the sheets having air emitting 40 perforations and the ends of the drum being open for admitting air, and means for drawing air into the drum through its open ends.

5. A drum comprising a plurality of segmental sheets, spiders including supports on which said sheets are fastened and arms forming fan blades set to draw air into the 50 drum as it revolves, said sheets having air emitting openings, and longitudinal beaters on the sheets contiguous to the air openings for deflecting the emitted air.

6. A drum comprising a plurality of elongated segmental sheets having flanges bent outward along their parallel edges, means for securing the flanges together, spiders including rings on which the sheets are mounted and radial arms in the form of fan 60 blades, and means for fastening the sheets on the rings of the spiders.

7. A drum comprising a plurality of elongated segmental sheets having flanges bent outward along their parallel edges, means for securing the flanges together, spiders in- 65

cluding rings on which the sheets are mounted and radial arms in the form of fan blades, means for fastening the sheets on the rings of the spiders, and pins fastened to the sheets between the flanges, each sheet having 70 a row of perforations contiguous to one of its flanges for emitting air.

8. A drum comprising a cylindrical member open at each end and having a plurality of air emitting openings in its walls, fan 75 blades mounted within the open ends of the cylindrical member, and screens mounted within the said member for intercepting the passage of lint, fibres and trash to the air emitting openings. 80

9. A drum comprising a cylindrical member open at each end and having a plurality of air emitting openings in its walls, of spiders mounted within each end of the member and each including a ring engaging 85 the member and fan blades carried within the ring, and screens mounted within the ends of the member contiguous to said spiders for intercepting the passage of lint, fibres and trash to the air emitting openings. 90

In testimony whereof I affix my signature.

JOSEPH BEHLE.
